ATTYS.

UNITED STATES PATENT OFFICE.

SAMUEL BUTTERWORTH, OF EVERETT, MASSACHUSETTS.

CUTTING-NIPPERS.

1,278,849.

Specification of Letters Patent. Patented Sept. 17, 1918.

Application filed December 31, 1917. Serial No. 209,743.

To all whom it may concern:

Be it known that I, SAMUEL BUTTERWORTH, a citizen of the United States, residing at Everett, in the county of Middlesex and State of Massachusetts, have invented new and useful Improvements in Cutting-Nippers, of which the following is a specification.

This invention relates to cutting nippers comprising a pair of levers fulcrumed on a supporting body, each lever having a longer and a shorter arm and a pair of cutters detachably secured to the shorter arms, the nippers also including operating levers fulcrumed on the body and having shorter arms engaging the longer arms of the cutter-carrying levers, and longer arms adapted to be manipulated to cause the cutters to forcibly approach each other.

10 The invention has for its object to provide certain improvements relating to the shorter arms of the cutter-carrying levers, and to the form of the cutters, whereby strains exerted on the cutters, tending to 15 displace the same from their operative positions, are resisted entirely by the said shorter arms and cutters, so that the relatively small screws employed to secure the cutters to the levers are entirely relieved 20 from the duty of resisting said strains.

The invention is embodied in the improvements which I will now proceed to describe and claim.

Of the accompanying drawings forming a 25 part of this specification,—

Figure 1 is a side elevation of a pair of cutting nippers embodying the invention.

Fig. 2 is a perspective view of one of the cutter-carrying levers, without the cutter.

40 Fig. 3 is an edge view of said lever.

Fig. 4 is a perspective view of one of the cutters.

Fig. 5 is a section on line 5—5 of Fig. 1.

Fig. 6 is a section on line 6—6 of Fig. 1.

45 The same reference characters indicate the same parts in all of the figures.

The body of the nippers includes a pair of parallel plates 12, these plates being connected by transverse screws 13 and 14, the 50 screws 13 constituting the fulcrums of the cutter-carrying levers, while the screws 14 constitute the fulcrums of the operating levers hereinafter described.

Each cutter-carrying lever 15 includes a 55 longer arm 15^a and a shorter arm 15^b, these being formed in one piece which is provided

with an orifice 17 to receive a fulcrum screw 13. The shorter arm 15^b is enlarged to form a transverse head 18. Said head is provided with a V-shaped cutter-receiving recess having two faces 19 and 20 which meet at an acute angle. The face 19 forms a side rest and the face 20 a back rest for a cutter 21. Said cutter is preferably substantially rhomboidal in cross section, and has a flat 60 inner side 22, formed to bear on the side rest 19, a cutting edge 23, a beveled back 24 formed to be seated on the back rest 20, and a flat outer side 25 parallel with the inner side 22. The cutting edge 23 is formed by 65 the intersection of the outer side 25 with the outer edge face 26 of the cutter.

The head 18 is provided with tapped orifices 27, and the cutter is provided with orifices 28 coinciding with the orifices 27, 70 said orifices being adapted to receive the shanks of attaching screws 29, the heads of which bear on the outer sides of the cutters.

It will be seen by reference to Fig. 1, that the inner sides 22 and beveled backs 80 24 of the cutters bear respectively on the side rests 19 and back rests 20 of the cutter-carrying levers, the arrangement being such that the back rests 20 coöperate with the beveled backs 24 in resisting strains tending to separate the cutters from the side 85 rests 19. The screws 29 are therefore relieved of the duty of resisting such strains, the function of the screws being simply to confine the cutters in place when the instrument is not in use. When the cutting edges 90 are pressed simultaneously against an interposed body to be cut, the strain or pressure exerted on the cutters holds them against the rests 19 and 20 the same as if the screws 95 29 were not present, the only function of the screws being to prevent the cutters from dropping away from said rests when the cutters are not in action.

It will be seen that a cutter formed to 100 fit the rests 19 and 20 is of extremely simple form, so that a workman desiring to replace a broken cutter can improvise a new cutter from a strip of steel, using appliances readily accessible in any machine shop. 105

Referring to Figs. 5 and 6, it will be seen that the plates 12 are spaced apart by two pairs of tubular struts, namely, two struts 30 which may be called a pair of outer struts, and two struts 31 which may be called a 110 pair of inner struts. The inner sides of the plates are countersunk to receive the ends

of the struts, and the screws 13 and 14 pass through the plates and the struts, said screws being threaded only at one end portion and engaged with tapped orifices in one of the plates 12, as clearly shown by Figs. 5 and 6.

5 The operating levers 32 are fulcrumed on the inner struts 31 and have shorter arms engaging the longer arms of the cutter-carrying levers, said longer arms being adapted to 10 be manipulated by the operator.

10 The struts 30 and 31 maintain the plates 12 suitably spaced apart and prevent the plates from binding on the interposed portions of the levers when the screws 13 and 15 15 14 are tightened.

15 The countersinks in the plates 12 and the ends of the struts projecting into said countersinks contribute materially to the strength 20 of the device. To compensate for the countersinking of the plate 12 having the tapped orifices engaging the screws 13 and 14, I 25 offset the said plate as shown at 12^a.

I claim:

1. Cutting nippers comprising a body, a 25 pair of cutter-carrying levers fulcrumed on the body, each lever having a longer and a shorter arm and a transverse head on the shorter arm provided with a V-shaped cutter-receiving recess, the faces of which meet at 30 an acute angle, one of said faces forming a side rest, while the other face forms a back rest, a pair of cutters each having a cutting edge, a flat inner side seated on said side

rest, a beveled back seated on said back rest, and a flat outer side, each head being 35 provided with tapped orifices and cutter-confining screws engaged with said orifices and having heads bearing on the outer sides of the cutters, the said back rests coöperating with the beveled backs of the cutters in resisting strains tending to separate the cutters from the side rests, so that the screws are relieved of the duty of resisting such strains, operating levers being provided for applying force to the cutter-carrying levers. 40 45

2. Cutting nippers comprising a body composed of parallel plates, a pair of tubular outer struts and a pair of tubular inner struts interposed between said plates, the plates being countersunk to receive the ends 50 of the struts, and headed screws passing through said plates and struts and engaging tapped orifices in one of the plates, a pair of cutter-carrying levers fulcrumed on the outer struts, each lever having a longer and 55 a shorter arm, cutters secured to the shorter arms of said levers, and a pair of operating levers fulcrumed on the inner struts and having shorter arms engaging the longer arms of the cutter-carrying levers, said struts constituting fulcrums for said levers and spacing members maintaining said plates suitably spaced apart.

In testimony whereof I have affixed my signature.

SAMUEL BUTTERWORTH.
